UNITED STATES PATENT OFFICE

ALEXANDER NYMAN, OF DOBBS FERRY, NEW YORK, ASSIGNOR TO DUBILLIER CONDENSER CORPORATION, OF NEW YORK, N. Y., A CORPORATION OF DELAWARE

VACUUM CONDENSER

Application filed September 3, 1924, Serial No. 735,572. Renewed May 26, 1931.

This invention relates to improvements in condensers comprising elements of electrically conductive material, separated one from another, for use in electric circuits.

5 An object of my invention is to provide an electrical condenser which can be operated at higher voltages and with smaller losses than have heretofore been deemed possible.

A further object of the invention is to provide an electrical condenser in which the electrically conductive elements are separated without the intervention of any gaseous, liquid or solid dielectric material whatsoever; preferably, by means of a construction from

15 the vicinity of which the air is exhausted, so that the condenser operates in a vacuum; although, in some instances, the conductive elements may be associated with intervening suitable dielectric material, while the vacuum 20 around the body of the condenser is maintained.

The nature of the invention and further objects and advantages thereof will be apparent from the following description and 25 drawings, and the novel features of my improvements are set forth in the appended claims, but the disclosure is, of course, illustrative only, and I may make changes in details, without departing from the scope and 30 principle of the invention, to the full extent indicated by the broad and general meanings of the terms in which the appended claims are expressed.

On the drawings,

35 Figure 1 is a sectional view taken through a condenser according to my invention, in a suitable container;

Figure 2 is a sectional view through another form of such a condenser;

40 Figure 3 is a top view of what is shown in Figure 2;

Figure 4 is a sectional view substantially on the line 4—4 of Figure 2; and

45 Figure 5 is a sectional view of a further modification.

On the drawings the same numerals identify the same parts throughout.

Heretofore, all electrical condensers have been so made that the construction thereof 50 included the use of a dielectric such as a suit-

able liquid, or solid material in the form of strips, sheets or plates, or as in an air condenser, a quantity of gas between the conductive elements or plates of the condenser. The presence of such insulation, although it 55 serves to separate the conductive elements electrically from one another, nevertheless, always gives rise to losses of some sort, such as brush discharges and current and voltage losses in the dielectric, although an air condenser with conductive plates of negligible resistance affords the advantage that it really sustains no losses except those due to the so-called brush discharge or corona.

In particular, with dielectric material of 65 some sort actually between the conductive elements of the condenser, there is also some transference of electrical energy between the conductive elements or plates of opposite polarity, such as brush discharges and creep- 70 age losses taking place across the dielectric itself, besides the current and voltage losses in the body of the dielectric. Some electrical energy always passes between the conductive elements or plates whenever the voltage is 75 high enough, because of brush discharge or creepage from one element to another. I have found it possible by providing a condenser to operate in a vacuum, to utilize much higher voltages than have heretofore been 80 permissible under practical conditions, and to obviate all the losses except eddy current losses in the metal parts of the condenser, and these losses can be made so small as to 85 require no consideration.

Referring first to Figure 1, I show at 1, in longitudinal section, an evacuated vessel, in the form of a bulb of glass or any other suitable material. Inside this vessel is the body 90 of a condenser 2, comprising members 3 and 4 which respectively carry the conductive elements or plates 5 and 6. The plates 3 and 4 appear in edge view in Figure 1, and the elements 5 and 6 in end view only. It will be understood that the plates 5 are arranged in 95 the usual way with their sides or faces parallel to one another and spaced the required intervals apart; while the plates 6 are given a similar arrangement projecting into the spaces between the plates 5 without making 100

contact therewith, the plates 5 being intended to be of opposite polarity with respect to the plates 6, and the plates 5 and 6 being disposed in alternation from one end of the condenser to the other. Hence, if the plates 3 and 4, which may be of some conductive material like metal, are joined to the opposite terminals of an electric circuit, the condenser will operate to provide the required capacity in said circuit. To the element 3, I may attach a wire or rod 7, sealing the end of same in the vessel 1, and to the member 4, I may attach a wire or rod 8, which is sealed in the vessel in the same way, the rods 7 and 8 serving as supports for the condenser 1, and I may also connect with the conductive member 3, a conductor 9 which is sealed in the side of the vessel 1 and passes out through the same to serve as a terminal, a similar conductor 10 being attached to the member 4 and being sealed in the vessel, extending through the latter to the exterior, to serve as another terminal. By means of the parts 7 and 8, the body 2 of the condenser is suspended inside of the vessel 1, out of contact with the interior surface thereof and if desired, the conductors 9 and 10 may assist in thus supporting the condenser, although the parts 7 and 8 may be large and strong enough to serve such a purpose by themselves.

The air is exhausted from the vessel 1 to such a point as to create a very high vacuum therein before it is sealed up over the condenser 2, and the vessel 1 with the condenser 2 in it can be disposed in a protective container 11 which completely encloses the container and may be filled with any suitable packing or cushioning material around the vessel 1 to prevent this vessel from being broken by handling or use, the packing or cushioning material thus protecting the vessel 1 with its contents from jars or shocks. The container may be provided with a removable top or cover which is provided with openings through which the conductors 9 and 10 may pass, and these openings may be covered with parts of insulation 12 and 13, forming binding posts and having threaded stems 14 to which the conductors 9 and 10 are attached, the threaded stems carrying on their outer ends nuts 15 to which the terminals of an electric circuit can be secured. The space between the interior surfaces of the container 11 and the evacuated vessel 1, to receive the packing and cushioning material, is indicated at 16, and the vessel 1 may be provided with depressions making reinforcing ribs 17 through which the parts 7 and 8 and the wires 9 and 10 are passed and in which they are sealed.

It will thus be seen that the construction of the condenser 2 and the manner of mounting the same in the evacuated vessel 1 dispenses with all insulation whatsoever between the elements 5 and 6. Hence, with all dielec-

tric material of any kind absent between the members 3 and 4, and the elements 5 and 6, there is nothing between the plates 5 and 6 to be ionized by the electric charge on the plates 5 and 6, and, therefore, no chance for current to flow between the plates 5 and 6. I thus can operate the condenser 2 in the vacuum within the evacuated vessel 1 at much higher voltages than the presence of dielectric between the plates 5 and 6 would permit. I also eliminate brush discharges and corona losses, together with current and voltage losses which usually take place in the dielectric material itself, and although there may be some eddy current losses in the metal plates 5 and 6, or the parts 3 and 4, these losses can be made so small that they can be left out of account. Of course, the members 3 and 4 do not have to be of metal, they can more suitably be of some other material, but all of the plates 5 must, of course, be electrically connected to themselves and to the conductor 9, and the plates 6 must be connected together and to the conductor 10.

While the absence of all dielectric material between the plates 5 and 6 is preferred, I may, in some instances, use solid dielectric between the various plates 5 and 6 in the evacuated vessel 1. I can then operate the condenser with the same high voltages as before without brush discharges or corona losses, although with dielectric present, some losses in the dielectric will necessarily take place.

In Figures 2, 3 and 4, I show an evacuated vessel 1 with transverse depressions 17 in the bottom of each of which is sealed a pair of rods 18, which are bent away from each other towards the opposite sides of the vessel and then bent so as to be parallel with each other as indicated at 19, these parts 18 being connected by transverse members 20, which may be wires or rods, to act as supporting bars for the conductive elements 5' and 6'. Thus there will be at one end of the bulb or vessel 1, a pair of parallel bars 20 to which the elements 5' will be secured by soldering or in any other suitable way, and the elements 6' will be similarly secured to the supporting bars or members 20 at the opposite end. At least one of the parts 18 and one of the bars 19 at each end of the condenser 2 should be of conductive material, so that to the end thereof which projects through to the outside of the condenser, may be joined the conductors 21 and 22 of the circuit in which the condenser is to be used. The elements 5 and 6 are shown in side view in Figure 2; in top view in Figure 3, and in end view in Figure 4.

The elements 5' and 6' are shown at different levels in Figure 2, and elements 6' in broken lines in Figure 4 merely to distinguish elements 5' from elements 6'.

Figure 5 shows another form of an evacu-

ated vessel 1 in which the conductive elements 5' and 6' are mounted by having their ends affixed to the bottom of hollow bottle-shaped members 23 which may be of conductive material. The necks of these bottle-shaped members 23 project through the opposite ends of the vessel 1 and are sealed therein, the ends of the necks being closed as indicated at 24, and through the necks may extend conduits 10 or pipes 25 and 26 for the admission and withdrawal of any suitable cooling medium, such as air or liquid. The members 23 being of conductive material, the terminals 27 and 28 of an electric circuit can be affixed thereto, 15 so as to connect the elements 5' and 6' into said circuit.

In order to reduce the eddy current losses in all of the above constructions to a minimum, the conductive elements of the 20 condenser should be made very thin, and obviously, any suitable means may be employed to mount these plates in proper relation in the evacuated spaces forming the chamber containing the vacuum enclosed by 25 the vessel 1.

Of course, the particular type of condenser is not material to this invention, as I may vary the design of condenser widely and still be within the principle of this invention.

30 Having described my invention, what I believe to be new and desire to secure and protect by Letters Patent of the United States is:

35 1. The combination of an evacuated vessel, a pair of hollow members in said vessel, said members comprising conductive material, condenser armatures of opposite polarity affixed to said members and spaced apart, and conduits for admitting a cooling medium to 40 the interior of said members, and withdrawing said medium to control the temperature of said elements, said members projecting to the exterior of said vessel to enable said elements to be connected to an electric circuit.

45 2. The combination of an evacuated container, a condenser within said container, the condenser comprising conductive elements in spaced relation, terminals for the conductors 50 of opposite polarity, and means within the container for circulating a fluid medium for cooling said condenser.

55 3. The combination of an evacuated container, a condenser within said container, the condenser comprising conductive elements in spaced relation, terminals for the conductors of opposite polarity, and means within the condenser for circulating a fluid medium for 60 cooling the conductive elements.

65 4. The combination of an evacuated container, condenser plates of conductive material supported in spaced relation within the container, the supporting means being adapted to serve as a cooling means for the con-

denser, and terminals for the conductors of opposite polarity.

5. The combination of a containing vessel, condenser plates of conductive material supported in spaced relation within the vessel, the 70 supporting means for the plates being adapted to convey a cooling medium to the condenser.

6. The combination of a container, condenser plates of conductive material supported 75 in spaced relation within the container, the supporting means for the plates having openings therein adapted to be utilized for cooling purposes.

7. An electrical condenser comprising a casing having an evacuated portion, the condenser plates being within the evacuated portion of the casing, means within the casing for supporting the condenser plates, said supporting means forming a circulatory path 85 for a cooling medium for the condenser plates.

Signed at New York, in the county of New York and State of New York, this 27th day of August, A. D. 1924.
